NICHOLAS ALBERGAMO, OF CHARLESTON, SOUTH CAROLINA.

REGISTER-OPERATING MECHANISM.

1,257,443.

Specification of Letters Patent. Patented Feb. 26, 1918.

Application filed September 29, 1916. Serial No. 122,940.

To all whom it may concern:

Be it known that I, NICHOLAS ALBERGAMO, a subject of the King of Italy, and a resident of Charleston, in the county of Charleston 5 and State of South Carolina, have invented a certain new and useful Improvement in Register-Operating Mechanism, of which the following is a specification.

My present invention relates to register 10 operating mechanism embodying a register, a treadle operated circuit control mechanism, and electro-magnetic means disposed in operative relation to said circuit control mechanism and register to actuate the latter by 15 operation of the former.

The principal objects of my inventions are to provide automatic registers which are operated by persons passing over treadles, particularly useful for registering the number 20 of persons entering or leaving a building, such as a theater, or vehicles, boats, etc., where it is desirable to obtain accurate record, preferably without the persons being conscious of the counting; apparatus of the 25 character described where the actuating mechanism may be remote from the registering mechanism, or with the former in connection with a portable object, such as a gang plank, and at the latter at some point, 30 as on the boat, or on the wharf; and, apparatus of the character described which will register the persons passing over the treadle in one direction only.

Other objects of my invention will appear 35 in the following detailed description, taken in connection with the accompanying drawing, forming a part of this specification, and in which drawing:

Figure 1 is a diagrammatic view showing 40 electrical connections between a register and circuit control mechanism, the former being shown in elevation with a portion of the casing in section, and the latter in plan, with a portion of the tread surface broken 45 away, to disclose details.

Fig. 2 is a fragmentary plan view of the register.

Fig. 3 is an enlarged sectional view on the line 3—3 of Fig. 1, looking in the direction 50 of the arrow.

Fig. 4 is a view similar to Fig. 3, but showing the mechanism as having been operated to complete a circuit.

Fig. 5 is an enlarged sectional view on the line 5—5 of Fig. 1. 55

In the drawing, where similar characters refer to similar parts throughout the several views, A designates a register; B electro-magnetic means which will operate the said register; C an audible electrically operated 60 signal; and D, circuit control mechanism for the means B and signal C.

Referring first to the register A, it may be of any suitable type, in the example shown, comprising a plurality of dials 6 having 65 delineations 7 thereon, such as numerals; a shaft 8 on which said dials are mounted and arranged in any suitable manner to be progressively moved circumferentially one digit as the dial carrying the delineations 70 representing units is given one complete turn, or any dial of the set toward that bearing the delineation representing units; a ratchet wheel 9 carried by standard 10; a pawl 11 adapted to engage with the teeth 75 of said ratchet wheel; an oscillatable lever 12 mounted on a shaft 13 of wheel 9 and supporting the pawl 11; and, motion transmitting means 14, such as a gear 15 rigid with shaft 13, a co-meshing gear 16 on shaft 80 8, and a pawl 17 acting upon gear 15 preventing movement thereof except in one direction.

The electro-magnetic means B may comprise electro-magnets 18 including cores 19; 85 an armature 20 disposed in operative relation to said cores and oscillatable about a standard 21; a yieldable contact 22; a set-screw 23 engaging yieldable contact 22 and adjustable to limit the amplitude of oscillation of armature 20 in one direction; and, motion transmitting means 24 intermediate the armature 20 and the register A. The means 24 may include a yieldable arm 25 carried by armature 20; a lever 26 rigid 95 with lever 12 of register A; and, a link 27 between arm 25 and lever 26. If desired, the arm 25 may carry a standard 28, and a contracting spring 29 may be interposed between said standard and the free end of 100 pawl 11 opposite to that portion engaging the teeth of ratchet wheel 9. Thus, as the electro-magnets 18 are energized, the armature 20 is drawn toward the cores 19, and through motion transmitting means 24, the 105 pawl 11 is drawn toward the electro-magnet

means, advancing the ratchet wheel 9 one notch, and moving the dial 6 nearest gear 15 one digit.

The audible signal C may be of any suitable type, and in the example shown, is in the form of an electrically operated device including the usual bell 30 and tappet 31.

Referring now to the circuit control mechanism, it includes a treadle 32 capable of 10 conducting a current, as by being formed of conducting material, such as iron, said treadle capable of oscillation about a horizontal axis intermediate its forward margin 33, and rear margin 34, as by means of rollers 15 35, operating in tracks 36; a stationary contact 37 insulated from treadle 32 as by being mounted upon a base 38, such as cement; a stop, 39, such as a strip of insulating material arranged on an upright face of contact 37 as is clearly shown in Fig. 3 of the drawing; and, means 40, such as springs, 20 normally positioning the treadle 32 remote from the stop 39 and contact 37, with the lower face of the treadle above the upper 25 face of the stationary contact, as is clearly shown in Fig. 3 of the drawing.

It is preferred to form the rollers 35 substantially elliptical in cross section, and the tracks including an upper set of flanges 41 30 embracing the upper portion of the roller and a lower set of flanges 42 embracing the lower part of its respective roller, preventing oscillation of the treadle about an upright axis. It is also preferred to decline the 35 tracks 36 toward the stop 39 and stationary contact 37 for a purpose to be subsequently set forth.

When assembling the circuit control mechanism into operative relation to the electro-magnetic means B and the audible signal C, an electric generator 43 is provided, one pole 40 of which may be conductively connected with the treadle 32 as through wire 44, and in the example shown, the tracks 36, roller 45 35, and its shaft 45 grounded on treadle 32 being of conducting material. The other pole of the battery 43 may be connected with the electro-magnets 18 and armature 20 as by wire 46, and with one pole of the audible 50 signal C, as by wire 47. The stationary contact 37 is in conductive communication with the set-screw 23, as by wire 48, and the other pole of audible signal C, as through wire 49.

55 The operation of the apparatus is as follows:—

Assuming that a person approaches the treadle 32 in the direction indicated by arrow in Figs. 3 and 4, as the foot engages that 60 portion of the treadle adjacent the forward margin 33, the forward stride will force the treadle 32 into engagement with stationary contact 37, completing an electric circuit and operating the electro-magnetic mechanism B 65 and audible signal C. Inasmuch as the

track is declined toward said contact 37, the treadle will remain in engagement with the stationary contact until the person moves from the treadle, whereafter devices 40 will draw the treadle back to a normal position, 70 breaking the circuit. Should the person approach the circuit control mechanism in a direction counter to that indicated by arrows in Figs. 3 and 4, the foot engaging the treadle 32 adjacent margin 34 will first depress that 75 portion of the treadle and the treadle at margin 34 will engage the stop 39, or strip of insulating material, the treadle moving forwardly owing to the position of track 36 with respect to the stop 39. Inasmuch as 80 the springs 40 have a tendency to yieldably position the treadle remote from the stationary contact 37, the stride of the person will not throw the treadle so as to engage the stationary contact 37 and the circuit 85 of electro-magnetic means B will remain broken.

Changes in details of construction or wiring may be made without departing from the spirit or scope of my invention; but, 90

I claim:—

1. In an automatic circuit closer, the combination of a stationary contact, an insulating element in front of said contact, a treadle 95 capable of conducting a circuit, oscillatable about a horizontal axis intermediate its forward and rear margins, and movable to engage said insulating element or stationary contact, yieldable means for normally positioning said treadle remote from said stationary contact and element, with its lower face above the upper face of said stationary contact, and an electric circuit including said treadle and stationary contact to complete a circuit when said treadle engages said stationary contact. 100

2. In an automatic circuit closer, the combination of a stationary contact, an insulating element in front of said contact, a treadle capable of conducting current, rollers carried 110 by said treadle permitting the same to oscillate by the horizontal axis intermediate its forward and rear margins, tracks for said rollers guiding said treadle in a path of movement to engage said insulating element 115 or stationary contact, yieldable means for normally positioning said treadle remote from said stationary contact and element, with its lower face above the upper face of said stationary contact, and circuit conductors leading from said treadle and stationary contact, to complete a circuit when said treadle engages said stationary contact. 120

3. In an automatic circuit closer, the combination of a stationary contact, an insulating element in front of said contact, a treadle capable of conducting current, rollers carried by said treadle permitting the same to oscillate by the horizontal axis intermediate 125 its forward and rear margins, tracks for said 130

rollers guiding said treadle in a path of movement to engage said insulating element or stationary contact, said tracks declining toward said element and stationary contact, 5 yieldable means for normally positioning said treadle remote from said stationary contact and element, with its lower face above the upper face of said stationary contact, and circuit conductors connected to said treadle and stationary contact, to complete a circuit when said treadle engages said stationary contact. 10

NICHOLAS ALBERGAMO.
